Attorneys.

UNITED STATES PATENT OFFICE

ESTEL E. WILMETH, OF SAN BENITO, TEXAS

ROADWAY CRACK AND JOINT FILLER

Application filed August 1, 1929. Serial No. 382,677.

This invention relates to a highway fissure or joint filler, the primary object of the invention being to provide a device of this character which will be automatically guided along the fissure or joint being filled, to insure an even filling thereof, and eliminating the necessity of the operator guiding the device.

An important object of the invention is to provide a joint or crack filler including a container and a movable stem operating through the container, the stem being of a construction to act as a guide or conductor for the material passing from the container.

Another important object of the invention is the provision of an oval container, the oval construction of the container preventing rolling of the container in the hands of the operator, thereby eliminating wrist strain to the operator, and at the same time permitting the operator to use both hands.

Referring to the drawing:

Figure 1 is a side elevational view of a fissure or joint filler constructed in accordance with the invention.

Figure 2 is a sectional view taken on line 2-2 of Figure 1.

Figure 3 is a sectional view taken on line 3-3 of Figure 1.

Figure 4 is a sectional view taken on line 4-4 of Figure 1.

Referring to the drawing in detail, the device includes a container 5 which is substantially funnel shaped as clearly shown by the drawing. The sides of the container are slightly flattened defining a container which is oval in cross section, to the end that the container will not roll in the hands of the operator while in use, thereby eliminating wrist strain and at the same time permitting the operator to use both hands during the operation of the device.

A handle indicated at 6, and which is in the form of a bail has its ends secured to the container as by means of the bolts 7, the

upper portion thereof being provided with an opening through which the upper end of the rod 8 extends, the lower end of the rod carrying the plunger valve 9, which tapers to fit within the tapered discharge end of 50 the container 5.

As shown, the extremity 10 of the valve plunger 9 is so constructed that it will act as a guide for the container as it is being moved along a crack or fissure being filled, thereby 55 relieving the operator of the responsibility of guiding the device and at the same time insuring the filling of the crack or fissure, without smearing the material over the road surface adjacent to the opening being filled. 60

A bar indicated by the reference character 11 extends across the handle or bail and has its ends secured thereto by means of the bolts 12. This bar is provided with an opening to receive the rod 8, with the result that the rod may be readily and easily moved through the openings when it is desired to lift the valve plunger 9 from its closed position, to allow material to pass from the container. 65

Secured to the rod 8, at a point between 70 the bar 11 and bail 6, is a cross handle 13, which may be gripped by the hands of the operator to move the valve plunger 9 from its seat. A coiled spring 14 is disposed between the bail 6 and cross handle 13 and acts 75 to normally urge the rod 8 and valve plunger downwardly to close the discharge end of the container, when the cross handle 13 has been released by the operator. Thus it will be seen that when the guiding extremity 10 of the valve plunger 9 is positioned in an opening or fissure being filled, and the cross handle 13 is moved upwardly, material will flow from the discharge end of the container and pass over the valve plunger which acts 80 as a feeder to draw the material from the container. 85

When the cross handle is released, it is obvious that the spring will return the valve plunger to its normal or closed position. 90

I claim:

In a device of the class described, a funnel shaped body portion oval in cross section defining substantially straight sides and curved ends, a bar secured to one end of the body portion to be gripped by the operator in supporting the device, the substantially straight sides of the body portion being parallel to the path of travel of the body portion when the device is in use, and a valve for controlling the passage of material from the body portion.

In testimony that I claim the foregoing as my own, I have hereto affixed my signature.

ESTEL E. WILMETH.
